UNITED STATES PATENT OFFICE

CHARLES W. HOPES, OF GLENS FALLS, NEW YORK

DESIGN FOR A COMBINED LAMP, ASH TRAY, AND LIGHTER

Application filed August 2, 1929. Serial No. 32,280. Term of patent 14 years.

To all whom it may concern:

Be it known that I, CHARLES W. HOPES, a citizen of the United States, and a resident of Glens Falls, in the county of Warren and State of New York, have invented a new, original and ornamental Design for a Combined Lamp, Ash Tray, and Lighter, of which the following is a specification.

Reference is to be had to the accompanying drawing in which the figure is a perspective view of a combined lamp, ash tray and lighter showing my new design.

What is claimed is:

The ornamental design for a combined lamp, ash tray and lighter, as shown.

CHARLES W. HOPES.
